UNITED STATES PATENT OFFICE.

GEORGE II. KING, OF KANSAS CITY, MISSOURI, ASSIGNOR OF ONE-FOURTH
TO ADOLPH J. PRUDOT, OF HERMANN, MISSOURI.

DESIGN FOR A COMBINATION TOY.

SPECIFICATION forming part of Design No. 29,907, dated December 27, 1898.

Application filed November 1, 1898. Serial No. 695,187. Term of patent 14 years.

To all whom it may concern:

Be it known that I, GEORGE II. KING, of Kansas City, State of Missouri, have invented and produced a new and original Design for Combination Toys, of which the following is a full, clear, and exact description, reference being had to the accompanying drawing, forming a part thereof.

The accompanying drawing is a perspective view illustrating my design.

The leading feature of my design consists of a tubular body flaring at one end and having circular disks or wheels between its ends, two of said wheels embracing the tubular body and the other projecting into it.

A represents the body of the toy, having a cylindrical appearance throughout a portion of its length and made flaring at the end B and contracted at its other end in the representation of a whistle C. Three wheels E 20 F are located between the ends of the body A, the wheels F embracing said body and the wheel E projecting into it.

What I claim is—

The design for a combination toy herein 25 shown and described.

GEORGE II. KING.
